[57] **CLAIM**

The ornamental design for a blend, moisten and storage system for tobacco products, as shown and described.

DESCRIPTION

FIG. 1 is a left front perspective view of the blend, moisten and storage system for tobacco products showing my new design;

FIG. 2 is a left front perspective view thereof wherein a first cover is removed and the storage drawer has been opened; FIG. 3 is a left rear perspective exploded view thereof showing both covers, the aerating tray, the reservoir tray and the base;

FIG. 4 is a top plan view of the aerating tray;

FIG. 5 is a top plan view of the reservoir tray;

FIG. 6 is a bottom plan view of one cover;

FIG. 7 is a bottom plan view of the base;

FIG. 8 is a bottom plan view of the aerating tray; and,

FIG. 9 is a bottom plan view of the reservoir tray.
